UNITED STATES PATENT OFFICE

EUGENE R. LEIGHTON, OF NORTH ANDOVER, MASSACHUSETTS, ASSIGNOR TO JENNIE E. LEIGHTON, OF NORTH ANDOVER, MASSACHUSETTS

BOTTLE CAPPER

Application filed February 3, 1928. Serial No. 251,551.

This invention relates to a mechanism for capping milk bottles with the usual cardboard disk caps. An object of the invention is to provide a simple device which may be operated by hand or may be included in a bottle-capping machine, which is simple in construction and reliable in operation, and which is easily loaded with a relatively large supply of caps. A further object of the invention is to provide a capping mechanism capable of inverting each cap prior to its insertion in the mouth of a bottle as it descends from the magazine through a relatively short distance to the bottle mouth. 15 Thus a shorter and lighter mechanism is provided than has heretofore been available in mechanisms of this type. These and other advantageous features will be apparent to one skilled in the art from the following description of the device and from the drawing; of which,

Figure 1 is a front elevation of a mechanism embodying the invention.

Figure 2 is a side elevation of the same.

25 Figure 3 is a section on the line 3—3 of Figure 1.

Figure 4 is a sectional view similar to Figure 3, but showing the mechanism in a different position of operation.

30 Figure 5 is a fragmentary section of the lower portion of the apparatus showing the progress of a bottle cap therethrough.

Figure 6 is a section on the line 6—6 of Figure 2.

35 Figure 7 is a section on the line 7—7 of Figure 3.

Figure 8 is a perspective view of the ejector.

Referring to the drawings in detail, 10 represents a magazine in the general form of an upright tube adapted to receive a stack 11 of bottle caps which may be inserted, if desired, within a tubular holder 12 of paper or the like, in which they are commonly packaged. The bore of the holder 12 is large 45 enough to receive the stack 11 with a relatively loose fit so that the caps will slide down through the magazine readily by their own weight. The bore of the magazine 10 is preferably tapered at its lower end as at 13 50 so that the opening at its lower end is just

large enough to permit a cap to pass through. Secured to the magazine 10 at its lower end is a base member 14, this member being arranged with its upper surface between its contacting margins spaced from the lower end of the magazine 10 by a distance slightly greater than the thickness of a single bottle cap. The base member 14 is provided with a downwardly extending aperture 15 which has an opening in the upper surface of the member 14 approximately the size and shape of a cap, but laterally displaced from the bottom opening of the magazine 10, so that the upper surface of the block 14 projects partially across the bore of the magazine forming a 60 crescent-like shelf 16 which extends around slightly more than half the inner periphery of the bore of the magazine and supports the stack of caps therein. In order to release a cap from the stack, a suitable slide or ejector 65 17 is provided to reciprocate laterally on the upper surface of the base member 14. This ejector is adapted to engage the edge of the bottom-most cap in the stack and displace it laterally so that it clears the shelf 16 and 70 registers with the opening in the block 14, thus falling through the aperture 15. The portion of the ejector 17 which engages the caps successively may be of any desired shape, but as shown in Figure 8, this portion comprises an arcuate edge 18 having a curvature substantially equal to that of the edges of the bottle caps. The ejector 17 may be provided with a pair of guide runners 170 to prevent its sticking or jamming, these runners 75 sliding in suitable channels 171. In order to facilitate construction of the mechanism, the bottom of the magazine casting may be machined plane, the channels 171 and the clearance space for the slide 17 being cut in 80 the upper face of the base member 14. Clearance is also preferably provided between the magazine and base member at the side opposite to the slide 17, as at 172, this clearance being preferably increased by a bevel in the 85 edge of the magazine casting which gives an ejected cap more space in which to turn and which enables the operator to insert a feeler to displace a cap which may have become jammed as a result of imperfection of 100

form or other cause. Below the opening in the upper surface of the block 14 and extending about half-way thereacross, the base member 14 is provided with a moderately sloping surface 19 on which a cap which has been displaced from the shelf 16 impinges as it falls through the opening. The cap is thus turned on a diametral axis until it has the same slope as the surface 19. The cap thereupon slides 10 down off the edge of the slope 19 and on to the surface 20 of the base member 14 which has a considerably steeper slope. This turns the cap further on its turning axis as it slides down the face 20 as shown in Figure 5. Positioned 15 below the base member 14 is a block 21 which has a central aperture 22 slightly smaller than the size of the bottle cap. From the margin of the aperture 22, the wall of the block 21 rises with an outward flare in the 20 shape of a cup. A portion of the wall may be extended up as at 23 so as to provide a convenient sloping surface preferably concaved as at 24 in the path of a cap sliding from the surface 20 whereby the rotation of the cap 25 is continued, the cup-shaped wall of the block 21 serving to center the cap over the aperture 22. The wall of the block 21 extends also downwardly from the aperture 22 and its inner surface is likewise flared in the shape of 30 a cup adapted to rest on the top of a milk bottle and to center the aperture 22 over the mouth of the bottle, so that when a cap falls through the aperture 15, it is turned successively by the surfaces 19, 20 and 24 to an inverted 35 position over the aperture 22 and consequently directly over the mouth of the bottle. The block 21 is connected to the magazine 10 and the base member 14 so as to be vertically reciprocable thereto. The connecting 40 means may be in the form of a pair of suitable slides 25 which as shown in Figure 2 may be connected to the block 21 as by screws 26. Suitable vertical ribs 27 or other equivalent guiding means may be formed on 45 or secured to the sides of the magazine 10 to guide the slides 25 and to maintain them in upright position. A plate 28 may be provided to maintain each slide 25 between its guides 27. In order to actuate the ejector 50 slide 17, a pair of laterally extending lugs 29 may be provided therewith. Each of these lugs is adapted to project through a diagonal slot 30 cut in the slides 25 and may be formed integrally with one of the guide runners 170. 55 It will be at once apparent from Figure 2 that motion of the slides 25 up and down relatively to the magazine 10 will result in a lateral reciprocation of the ejector 17. The lower portion of the base member 14 is suitably 60 shaped as at 31 to form a plunger adapted to be projected downwardly through the aperture 22 and thus to force a bottle cap through the aperture and to seat it in the mouth of a bottle therebeneath. 65 The operation of the mechanism is as fol-

lows: When a stack of caps has been inserted in the magazine, the magazine may be raised relatively to the block 21. This retracts the ejector 17 to the position shown in Figure 3. The magazine 10 is thereupon lowered to the position shown in Figure 4, this motion causing the sidewise displacement of the bottom-most cap in the stack by the ejector 17, which cap falls onto and slides down the surfaces 19, 20 until its edge stubs the surface 24. The magazine is thereupon lifted to elevate it with relation to the block 21 and thus to retract the ejector 17, whereupon the cap slides down the surface 24, its upper edge tilts outwardly, and it then slides downwardly in inverted position over the aperture 22. The mechanism is then placed over a milk bottle to be capped and the magazine 10 is thrust downwardly. This causes the plunger 31 to force the cap which is over the aperture 22 through the aperture and into its seat in the mouth of the milk bottle. Simultaneously with this action, the ejector 17 displaces another cap from the bottom of the stack as shown in Figure 4, this cap proceeding to fall into place over the aperture 22 as the magazine is raised and into position to be seated on a bottle on the next downward stroke of the magazine. Thus the operation may be repeated as long as a supply of caps is maintained in the magazine. Inasmuch as each cap is inverted before being inserted in a bottle mouth, it is obvious that the caps should be inserted in the magazine upside down so that any printing matter thereon will be on their bottom faces as they are positioned in the magazine. This is convenient to the operator who naturally opens the top of a container of a stack of caps to see that the correct printed matter is thereon, then in the case of a machine capper inverts the stack and inserts its top end down-most into the magazine, whereupon the magazine is ready for operation. Where the capping is done by hand, it is usually more convenient to invert the capper and bring it down over the stack holder 12, the top end of which has been opened. The capper and holder are then turned right side up and the holder 12 slightly withdrawn to bring its lower edge above the tapered portion of the lower end of the magazine bore to free the lowest caps.

Having thus described certain embodiments of this invention, it should be evident to those skilled in the art that various changes and modifications might be made therein without departing from its spirit or scope as defined by the appended claims.

I claim:

1. A device of the class described, comprising a tubular member having a bore adapted to receive and hold a stack of milk bottle caps, means for removing a cap from the bottom of said stack, an apertured block adapted to

rest on the top of a milk bottle with its aperture registering with the mouth of the bottle, said aperture having a diameter slightly less than that of a cap, and a plunger movable through said aperture, said block and plunger having cooperating guide surfaces for inverting a cap after its removal from the bottom of the stack.

2. A device of the class described, comprising an apertured block adapted to rest on top of a milk bottle, means for forcing a cap through said aperture to seat in the mouth of said bottle, said means comprising a plunger vertically reciprocable relatively to said block, means extending upwardly from said block for guiding the motion of said plunger, said guide means having an inclined slot therein, and means for feeding a cap to said block, said feeding means including an ejector mounted to move vertically with said plunger and to slide horizontally relatively thereto, said ejector having a lug engaging in said slot whereby motion of the plunger relative to the block causes transverse motion of the slide.

3. A device of the class described, comprising an upright tubular magazine for milk bottle caps having a plane lower face with a circular opening therein of slightly larger size than that of a bottle cap, a base member secured to the bottom of said magazine, the upper surface of said base member being depressed to provide a clearance between the magazine and member slightly greater than the thickness of a cap, said upper surface also having a pair of parallel channels therein and a circular opening slightly larger than a flat area of a bottle cap and offset relatively to the opening in the bottom of the magazine, thus forming a crescent-shaped shelf below said magazine to support caps placed therein, an ejector slide reciprocable in said clearance between the magazine and base member, said slide having runners fitting in said channels, means for operating said slide to displace the bottom-most cap from said shelf, and means for inverting the released cap and seating it in the mouth of a bottle.

4. A device of the class described, comprising an apertured block having a circular recess in the bottom thereof adapted to receive the top of a milk bottle and a circular recess in the upper part thereof adapted to receive a bottle cap, a tubular magazine vertically disposed above said aperture and adapted to receive and hold a stack of bottle tops, a plunger secured below said magazine and reciprocable therewith relatively to said block, said plunger having an upper surface extending part way across the space beneath the magazine with a moderate slope and the rest of the way with a steep slope in the same direction, means associated with said magazine for supporting a stack of caps therein, and an ejector transversely movable to re-

lease the bottom cap from the stack and to permit it to fall on the sloping surfaces of said plunger, said block having a face sloping in the reverse direction to cooperate with said plunger to invert a cap released from the stack during its descent therefrom into the upper recess of the block.

5. A device of the class described, comprising an upright tubular magazine for milk bottle caps, a base member secured to the lower end of said magazine, said base member having an aperture therethrough with an opening at its upper face substantially equal to the cross section of the bore of the magazine but laterally offset therefrom so that a portion of the upper face of said base member forms a shelf below said magazine to support a stack of caps therein, said base member having below said opening a moderately sloping surface extending about half-way across said opening and terminating in a surface sloping steeply in the same direction, a slide movable on the upper face of said base member to displace laterally the bottom-most cap in said magazine so that the cap registers with and falls into said opening and is successively turned on a diametral axis as it slides down said moderately sloping and steeply sloping surfaces, a block adapted to engage on the top of a milk bottle, said block having a central aperture slightly less than the size of a cap and a cup-shaped wall rising from said aperture, the cup-shaped wall of the block having a portion sloping in a direction transverse to that of the inclined surfaces of the base member, means connecting said block with said magazine and base member and guiding relative vertical reciprocation therebetween, said block being located so that when the magazine is in relatively elevated position, a portion of the side wall of the block sloping in a direction transverse to that of the inclined surfaces of the base member is in position to receive a cap sliding off said steeply sloping surface and to complete the turning of the cap to an inverted position, said base member having a plunger portion arranged to project downwardly through the aperture in said block when the magazine moves to its lowered position, and means for reciprocating said slide laterally when the magazine is raised and lowered with respect to said block.

6. A device of the class described comprising a magazine for a vertical stack of milk bottle caps, an apertured block vertically reciprocable below said magazine, said block being adapted to rest on the top of a milk bottle and to center a cap for insertion in the mouth of the bottle, means for pressing a cap centered in said block through the aperture thereof, a pair of supporting guides extending upwardly from said block for vertical reciprocation therewith and slidably se-

cured to said magazine, each said guide having an inclined slot therein, and a horizontally reciprocable cap ejecting slide having laterally extending lugs engaging in the slots of the respective guides whereby vertical reciprocation of the block results in horizontal reciprocation of the ejecting slide.

In testimony whereof I have affixed my signature.
